TENTER CLIP

Frank Chester Jerauld and Harry A. MacKnight,
Cranston, R. I., assignors to Winsor & Jerauld
Manufacturing Company, Providence, R. I., a
corporation of Maine

Application December 9, 1948, Serial No. 64,306

1. Claim. (Cl. 26—62).

1

This invention relates to improvements in tenter clips. More especially it has to do with tenter clips capable of traveling at high speed without danger of breakage and with a minimum of wear as they travel along the rail of a tentering machine.

Heretofore tenter clips have been made almost entirely of castings with the body and arch member usually formed integrally from malleable iron. Chains comprising such clips usually travel at from fifty to one hundred yards per minute along the tenter rail without serious trouble, although the wear of certain portions of the clip has always been large and undesirable despite ample lubrication. With the present advent of much higher speeds of travel of the cloth, of the order of from one hundred fifty to two hundred yards a minute, the clips heretofore available have in many instances broken and the wear has been so excessive as to be prohibitive.

It is accordingly an object of the present invention to provide a tenter clip having its parts made of materials best adapted for the particular functions of the parts and with the parts so shaped and secured to one another that the clip as a whole is exceedingly rugged and long-wearing. It is a feature of the construction that certain plates which are subject to the greatest sliding contact are made by stamping them from sheet steel stock having a high resistance to wear. The parts normally in contact with the cloth being processed are made of stainless steel which in itself insures continued cleanliness, and a guard plate is also provided to prevent any lubrication from reaching these cloth engaging parts. Another feature in the improved clip resides in the construction of the jaw, especially the means which enable the blade to be held clear of the cloth until the very edge of the cloth is clipped tightly by the blade. The improved method in constructing the clip and the selected materials of which it is made, combine to produce a clip which is exceedingly strong which can be run safely at high speed and which has outstanding wearing qualities.

The best mode in which it has been contemplated to apply the principles of the present invention is shown in the accompanying drawings but these are to be deemed illustrative because it is intended that the patent shall cover by suitable expression in the appended claim whatever features of patentable novelty exist in the invention disclosed.

In the accompanying drawings:

2

Fig. 1 is a front elevation of the improved tenter clip embodying our inventions;

Fig. 2 is a bottom view of the cam plate;

Fig. 3 is a side elevation of the clip taken as on line 3—3 of Fig. 1 showing a piece of cloth held by the clip;

Fig. 4 is a plan view of the clip as shown in Fig. 1;

Fig. 5 is a side elevation in section taken as on line 5—5 of Fig. 4; and

Fig. 6 is a section in elevation taken as on line 6—6 of Fig. 4.

The improved clip as a whole comprises a base plate 10, an arch member 12 secured thereto and carrying a jaw 14, a bearing plate 16 also secured to the base plate and coacting with a blade 18 on the jaw to hold the cloth C, links 20 and 22 and rollers 24 rotatably attached to the base plate, a cam plate 26, and a shield 28 which prevents the lubrication from reaching the cloth being operated upon by the tentering machine.

Referring now more particularly to the drawings, a base plate 10 is stamped from sheet steel, the greater portion being flat but having its entire front portion turned upward as at 10a and then turning again to extend forward at 10b parallel to the said greater flat portion. It is understood that although the terms "turned" and "turning" have just been used in the description of this base plate, no actual turning of the metal is made except as occurs during the stamping operation.

Along its transverse center line the base plate 10 is also pressed upward to form a flat topped ridge 10c whose top side is in alignment with the upper surface of the front end 10b. To this ridge and the front end is attached a bearing plate 16 made of stainless steel and preferably secured to the base plate by projection welding. Both this bearing plate 16 and the ridge 10c of the base plate have one or more grooves or slots 10d and 16a respectively cut therein for a purpose to be presently described. The ridge 10c of the base plate at its inner or left end as seen in Fig. 5 is somewhat rounded and serves as a guide in positioning an arch member 12 on the base plate.

This arch member 12 has outstanding flanges 12a at its lower end which are secured to the base plate 10 preferably by projection welding them together. The upstanding portion of the arch member is generally hollow, as it were, as best shown in Fig. 5 and at its forward end is forked to provide bearings 12b and 12c for an axle

pin 30 on which is carried a jaw 14. This arch member is made from steel by a drop forging operation.

The jaw 14 is a bronze casting having a body portion 14a with upstanding arms 14b and 14c at each end which also provide bearings for the axle pin 30. From the center of the body portion another arm 14d extends upward with a hole 14e through it which serves for still another bearing for the axle pin 30. Beyond the pin, 10 this middle arm 14d constitutes a handle which at the entering and delivery ends of the tentering machine is engaged by suitable cams to cause the jaw to swing clockwise, as seen in Fig. 3, to allow the cloth to enter the clip or to release the cloth therefrom as the case may be.

The body portion 14a of the jaw has inserted along its lower edge a stainless steel blade 18 which is held in the jaw by means of rivets or bolts 19 and is sharpened to a knife edge, not so sharp as to cut the cloth but still sharp enough to bite into the cloth and coact with the bearing plate to hold the cloth securely in the clip.

On the rear side of the body portion 14a of the jaw is another arm 14e which is preferably slotted to provide several shoes 14f which are aligned with the several slots or grooves in the bearing plate 16 and the ridge portion 10c of the base plate. The distribution of the weight of the jaw is such that it tends constantly to swing counterclockwise as seen in Fig. 3.

When the cloth first enters the tenter chain, the latter is so positioned that the cloth extends well under the arch as shown in Fig. 5. The cloth then overlies the slots 16a and 14d and the shoes 14f of the jaw rest on the cloth and so position the jaw that the blade 18 is kept out of contact with the cloth. The tenter chains as they move forward on the machine diverge as desired and soon the cloth slips from under the shoes 14f of the jaw. They immediately drop into their respective slots and at the same time the blade 18 engages the cloth and coacts with the bearing plate 16 to hold the cloth firmly to the clip as the latter proceeds forward in the machine. (See Fig. 3).

The base plate has sidewise extending portions 10e and 10f by which the plate is attached to links 20 and 22 and a cam plate 26. The details of this connection are shown in Fig. 6. A rivet 32 extends downward from the base plate through a sleeve 34 which has around it an upper link 20, a roller 24 and a lower link 22. Between the base plate and a shoulder 32a on the rivet is secured a shield 28 which extends forward and is finally bent upward to engage the inner end 10b of the base plate. This shield prevents any oil or grease from passing upward through the slot or slots in the base and bearing plate and thus avoids any damage to the cloth as has heretofore been caused by the lubrication used on the tenter chain and rails. At the bottom of the rivet 32 another shoulder 32b is engaged by the cam plate 26 which is stamped from sheet steel stock. It is to be noted that these shoulders on the rivet are so spaced that the sleeve, links and roller have ample clearance from the shield and the cam plate to turn easily. After the ends of the rivets are headed over, any excess of metal is ground off, especially at the lower end of the rivet so that the cam plate 26 and the rivets will have a smooth surface.

The outside diameter of the rollers 24 is slightly greater than the width of the links and the cam plate so that as the chain moves along the machine the rollers roll along a casing member 38 (see Fig. 5) which is secured to the rail 38 of the tentering machine. The cam plates 26 slide along the finished top surface of this rail with a minimum of friction due to the smooth surface of the cam plate and rivets. Also secured to the rail is a top casing member 40, a flange of which overlies the rear portion of the base plate 10 and has a finished surface which is engaged by the base plate 10 of the clip to prevent the latter from turning toward the cloth. Here again the friction is very small due to the smooth surface of the base plate.

As shown in Figs. 1 and 4, the links 20 and 22 are common, so to speak, with the next adjacent clips, and thus the complete chain is built up. In order that the clips shall retain their proper position and relation to one another the cam plate 26 is provided at one end (see Fig. 2) with a tongue 26a and at the other end with a recess 26b. As the chain moves along the rail these cam plates keep the links in proper alignment and assure proper gripping and holding of the edge of the cloth. At the ends of the machine the chain and clips turn around on sprocket wheels and when these wheels are reached the tongues 26a and recesses 26b enable the clips to turn relative to one another as the chain passes around with a sprocket and reverses its direction.

We claim:

1. A tenter clip having a base plate, a bearing plate secured to said base plate, aligned slots in said base plate and said bearing plate, an arch member secured to said base plate having a portion extending over and beyond said slots, a jaw member rotatably mounted on said portion having a blade arranged to coact with said bearing plate to clamp cloth between them and having a shoe portion aligned with said slots, the said blade being held out of engagement with the cloth when the latter overlies the said slots and the said shoe portion rests on the cloth and said blade being engageable with the cloth when the said shoe portion swings downward within said slots, a pair of rivets secured to said base plate on opposite sides of said arch member, a guard plate secured to said base plate by said rivets and extending beyond said slots, a pair of links with interposed roller rotatably mounted on each rivet, and a cam plate secured to each rivet at the end thereof opposite said base plate.

FRANK CHESTER JERAULD.
